UNITED STATES PATENT OFFICE.

WALTHER RASTER, OF CHICAGO, ILLINOIS.

REINFORCED CONCRETE CONSTRUCTION.

No. 921,626.

Specification of Letters Patent. Patented May 11, 1909.

Application filed June 22, 1908. Serial No. 489,790.

To all whom it may concern:

Be it known that I, WALTHER RASTER, citizen of the United States, residing at Chicago, in the county of Cook and State of Illinois, have invented certain new and useful Improvements in Reinforced Concrete Constructions; and I do hereby declare the following to be a full, clear, and exact description of the invention, such as will enable others skilled in the art to which it appertains to make and use the same.

This invention relates to a novel reinforced concrete construction and more particularly to a concrete beam, the object being to provide a device of this character which is comparatively light in proportion to its strength and is equipped with means for readily handling the same and with means for passing and supporting ducts such as gas and water pipes and electric wires, and consists in the features of construction and combinations of parts hereinafter fully described and claimed.

In the accompanying drawings illustrating my invention: Figure —1— is a central vertical longitudinal section of a beam constructed in accordance with my invention showing the same mounted between two floor joists. Fig. —2— is a similar fragmentary view on an enlarged scale showing one end of the beam and the manner of reinforcing the same. Fig. —3— is a fragmentary transverse section of a floor composed of beams constructed in accordance with my invention. Fig. —4— is a similar view on an enlarged scale showing a modified form of construction. Fig. —5— is a fragmentary top plan view of a beam showing the upper reinforcing rods looped at their ends.

The growing use of reinforced concrete in buildings has demonstrated that unless this material is mixed by skilled persons and properly applied, accidents are not unlikely to result.

The usual method employed in constructing the horizontal partitions of buildings, constituting the floors, is to construct molds bordered by the beams into which the concrete is introduced and allowed to set, whereupon the mold bottom or support is removed and the molded body then constitutes a slab. The strength of the slab is dependent upon many well known contingencies and even though very carefully made of the best materials its actual carrying capacity remains problematical in view of the absolute lack of any thoroughly reliable data on the strength

of reinforced concrete. In view of this it is customary among engineers to specify thicknesses which are unquestionably safe with reasonable care in construction, and as a consequence excessive weight results, where probably, economy could be exercised without danger.

The object of my present invention is to provide a substitute for molded slab and beam sections in the shape of beams which can be made and tested at the factory before shipment and installation, whereby uniformity of materials and methods is assured and weight minimized.

The beams are preferably of inverted U-shape in cross section and comprise the web or slab A and the flanges or legs B, the latter being connected at intervals by cross flanges C. The said beam is reinforced by embedded steel rods D extending longitudinally through the free end portions of the flanges or legs B and similar but considerably lighter rods E extending longitudinally through the elbow portions of the beams, said rods being primarily connected together by means of wires F secured at their ends to the rods D and between their ends coiled around the rods E, said wires F being disposed at intervals according to requirement of stresses parallel with each other and either perpendicular or inclined relatively to said rods D and E.

The heavy rods D take up the tensile stresses in the flanges or legs B of the beams.

The portions of the wires F lying between the rods E serve to take up tensile stresses in the slab A, the said rods E serving to distribute and transmit such stresses. Thus the slab A becomes a compression member longitudinally and laterally, the tensile stresses which would mainly be felt in the lower part of said slab being taken up by the said wires F which are embedded below the middle thereof. The ribs C further support the slab and take up lateral stresses thereon, and serve to distribute the load. The said beams are mounted side by side to form a floor and are provided on the outer faces of their flanges with parallel longitudinal ribs of varying projection between which grooves G, H and I are formed. The latter serve when the beams are disposed side by side to form ducts to which access is had through slots J, K and L respectively formed between the opposing faces of ribs of lesser projection of adjacent beams. The heads of anchors M and hangers N are adapted to pass through

the slots K and L and engage said ribs of lesser projection, said anchors serving to secure sleepers O and the hangers N to secure a ceiling P suspended below the beams.

5 The beams are supported at their ends on the joists Q which in the instance illustrated consist of steel I-beams.

The concrete beams are relatively very heavy and correspondingly difficult to handle, hence, it is essential that the weight be considered in providing means for mounting the beams. The latter are made of less length than the shortest distance between the webs of opposed I-beams but preferably 15 longer than the distance between the free edges of the opposed flanges of opposed beams so that the concrete beam may be inclined and one end thereof swung underneath one flange of an I-beam and the other end

20 then lowered to pass the flange of the other I-beam as the concrete beam assumes a horizontal position. The latter is then moved longitudinally until centered between the I-beams. On the lower opposed flanges of 25 the latter are mounted chair blocks R having beveled upper faces upon which the beveled ends of the concrete beams rest, the latter thus serving to hold said chair blocks in place.

30 The slab portions of the beams project above the upper faces of the I-beams and are cut away at their upper end corners to provide free spaces S into which grouting is introduced, the latter filling the spaces between the webs of the I-beams and the ends 35 of the concrete beams. The sleepers shown in Fig. —3— extend transversely to the concrete beams on which they rest and the anchors securing the same are provided at 40 their upper ends with eyes through which nails are preferably driven. Where transversely disposed sleepers are used it is necessary or at least customary to fill up the spaces therebetween with cinders, etc., to 45 deaden noise. To avoid this, the upper corners of the beams may be cut away to provide recesses for the reception of sleepers W which are anchored in place by means of toggle bolts X.

50 Recesses Y are provided in the grooved ends T of the concrete beams to receive the

upper flanges of the I-beams, said recesses being also filled with grouting which covers the said I-beams. The concrete beams are thus firmly secured in place and the I-beams 55 completely embedded between chair blocks and by the grouting.

The rods E project at their ends from the ends of the slab A and are bent back to re-enter the same thereby forming loops U 60 which receive the legs of inverted U-shaped anchors V passing over the I-beams and serving to connect beams disposed on opposite sides of the I-beams, said anchors becoming embedded in the grouting previously referred to.

It will be noted that the flanges B are provided with openings Y' for the passage of pipes and wires, and openings Z are provided in the slab to afford suitable means for 70 handling the beams.

I claim as my invention:

1. An inverted U-shaped beam equipped in the free end portions of its flanges and in its elbow portion with embedded longitudinally disposed reinforcing rods, and having embedded therein transverse reinforcing wires secured at their ends to the rods in the flanges and secured between their ends to the rods in the elbow portions said connections 80 between said rods and said wires being made by winding the latter around the former.

2. An inverted U-shaped beam equipped in the free end portions of its flanges and in its elbow portion with embedded longitudinally disposed reinforcing rods, and having embedded therein transverse reinforcing wires secured at their ends to the rods in the flanges and secured between their ends to the rods in the elbow portions, said rods in 90 the free ends of said flanges being of greater thickness than said rods in said elbow portions and said connections between said rods and said wires being made by winding the latter around the former.

95 In testimony whereof I have signed my name in the presence of two subscribing witnesses.

WALTHER RASTER.
